MACHINE FOR REINFORCING METALLIC SHEETS

George E. Kentis, Cleveland, Ohio, assignor to
The Yoder Company, Cleveland, Ohio, a corpora-
tion of Ohio

Application August 3, 1938, Serial No. 222,890

12 Claims. (Cl. 153—77)

This invention relates to a machine for automatically embossing sections of sheet metal, for example sheet metal sections to be used as roofing wherein the lateral sides of the sections have 5 interlocking relation with adjoining sections and the outer ends of the sections overlap the adjoining forward sections in a manner to prevent intake of water due to capillary attraction.

One object of the invention is to provide an 10 improved machine of this character wherein sheet metal sections may be fed to and through the machine and automatically embossed transversely to their direction of movement.

Another object of the invention is to provide 15 an improved machine of this character capable of embossing sheet metal on lines parallel to and transversely to their direction of movement.

Another object of the invention is to provide an 20 improved machine of this character wherein sections of sheet metal are fed therethrough and embossed, the sections serving as the means for operating the embossing devices.

A further object of the invention is to provide 25 an improved machine of this character that is relatively simple and has large capacity.

Other objects of the invention will be apparent 30 to those skilled in the art to which my invention relates from the following description taken in connection with the accompanying drawings, wherein

Fig. 1 is a side elevation of a machine embodying my invention.

Fig. 2 is a plan view thereof.

Fig. 3 is a fragmentary longitudinal section on 35 the line 3—3 of Fig. 4.

Fig. 4 is a section on the line 4—4 of Fig. 3.

Fig. 5 is a fragmentary side elevation on the 40 line 5—5 of Fig. 4.

Fig. 6 is a fragmentary section on the line 6—6 of Fig. 4.

Fig. 7 is a view on the line 7—7 of Fig. 6, parts being in section.

Fig. 8 is a plan view of a section of sheet metal showing the manner of embossing it as it feeds 45 through the machine.

Fig. 9 is an end view of the section looking towards the right in Fig. 8.

Fig. 10 is a section on the line 10—10 of Fig. 8.

Fig. 11 is a fragmentary section on the line 50 11—11 of Fig. 12, showing a modified form of embossing mechanism.

Fig. 12 is a section on the line 12—12 of Fig. 11.

In the drawings, 1 indicates as an entirety a 55 frame forming a support for a plurality of pairs

of standards 2, 3, 4, 5, 6, 7, 8 and 9. The standards 2, 3, 4, 5, 6 and 7 are shaped to form guides and seats for upper and lower pairs of bearing boxes 10, which removably support upper and lower shafts 2a, 3a, 4a, 5a, 6a and 7a. The shafts extend beyond the standards at one side of the frame 1, the extended ends of each upper and lower shaft being geared together to rotate in opposite directions and one thereof being drivingly connected to a shaft 11, the gearing between each upper and lower shaft and the driving connection with the shaft 11 being enclosed in a housing 12. The shaft 11 is provided with a pulley or sprocket 13 driven by an endless member 14 from a pulley or sprocket 15, which is 15 fixed to the shaft of a motor 16.

The upper and lower shafts 2a, 3a, etc. are provided with rolls 2a', 3a', 4a', 5a', 6a', 7a', respectively. Each roll may be integral with the adjacent shaft or removably mounted thereon; 20 in this latter arrangement each roll may be formed as a single member or in sections and suitably keyed to the shaft.

Each section of sheet material A is delivered 25 to the first set of rolls 2a' manually or by a suitable delivery mechanism (not shown), being positioned on a guide indicated as an entirety at 17 disposed in position to direct the sections between the rolls 2a'. The guide 17 consists of a pair of spaced brackets 17a having cross bars 17b, angles 17c being secured to the arms of the brackets 17a and an intermediate supporting strip 17d being mounted on the bars 17b.

The sections of sheet metal A are embossed 30 longitudinally along their lateral sides, as shown at a, a', a^x and by preference the sections are embossed longitudinally between its lateral portions, for example, centrally, as shown at B; the sections are also embossed transversely as shown at C, C', at either side of the embossment B; but 35 where the embossment B is omitted, the embossments C, C', may extend entirely across the ends of the sections within the embossments a, a'. When laid in position to form a roof, the embossments a, a', a^x, provide for an interlocking relation between each section and the adjoining sections, whereas (a) the embossments C, which are disposed adjacent the outer end of each section, overlie the inner end of the adjoining outer section and form a space between 40 their overlapping portions so that water cannot, due to capillary attraction, work up under such section and (b) the embossment C', which is bent downwardly relative to the plane of the section, serves to engage the adjoining section 45 50 55

under pressure when the section is secured in position.

To form the embossment B as each section of material moves between the sets of rolls, 2a', 3a', etc. each upper roll is formed with a substantially V-shaped circumferential groove 18 and each lower roll is provided with a circumferential rib 19 complementary to the adjacent groove 18, the grooves and ribs being in alignment and progressively increasing in depth and height respectively, so that during movement of each section A between the sets of rolls, the embossment is gradually formed, as shown in Fig. 8. The embossments a, a', a^x are formed by the sets of rolls 4a', 5a', 6a' and 7a'. For this purpose, the opposite ends of the upper roll 4a' terminate in inclined walls 20 and reduced circular ends 21 and the adjacent lower roll is complementary shaped at its opposite ends. Each of the remaining upper rolls 5a', 6a', 7a' is formed at its opposite ends with circumferential grooves 22 and each adjacent lower roll is provided at its opposite ends with complementary annular ribs 23 the depth of these grooves and height of the ribs progressively increasing. As shown in Fig. 2, the sets of rolls 6a', 7a', at one end are shaped to form the embossment a^x.

24, 25, indicate a pair of co-acting devices disposed upon opposite sides of the path of movement of the sections and movable from the rear side of an imaginary median line to the forward side thereof and provided on their opposed faces with transversely extending complementary embossing elements 26, the elements on the lower member intersecting the plane in which the sections A move, so that the sections, in passing through the co-acting devices, are embossed upwardly as shown at C and downwardly as shown at C' (see Figs. 8, 9 and 10).

40 In the form of construction shown in Figs. 1 to 7, inclusive, the embossing devices 24, 25, consist of a pair of members respectively keyed to upper and lower rock shafts 24a, 25a, mounted in the bearing boxes 10, which are supported in the standards 8, the extended ends of the shafts 24a, 25a, being provided with segmental gears 27 in mesh with each other, whereby the shafts rock simultaneously in opposite directions. Each member 24, 25, consists of a sleeve 28 keyed to the adjacent shaft and radially extending arms 29, to the outer ends of which are suitably bolted plates 30 provided on their outer sides with embossing elements 26, the embossing elements 26 on one member being complementary to the embossing elements on the other member. By preference, the plates 30 are provided with a plurality of sets of embossing elements 26 to provide two parallel embossments C at either side of the embossment B and a downwardly extending terminating edge 60 or embossment C'. By preference, I provide an arm 29 at each end of each member 24, 25, and an arm 29 midway therebetween. As will be understood from Figs. 4, 6 and 7, the arms 29 on the member 24 are formed with recesses 29a and the arms 29 on the member 25 are provided with ribs 29a' to accommodate the embossments a, a', a^x, and B as the sections A pass between the members 24, 25. Means are provided for normally biasing the members 24, 25, to a predetermined position ready to receive a section A between them, as shown in Figs. 3 and 5. For this purpose one gear segment 27 is provided with an arm 32 to which one end of a spring 33 is connected, the opposite end of the spring being suitably anchored, and normally tends to swing the mem-

bers 24, 25, to the position referred to against a stop 34. The stop 34 preferably consists of a bolt threaded through a bracket 34a, whereby its free end may be adjusted to limit the movement of the gears 27 at the desired position. The bracket 34a may be provided with a threaded shank and screwed into the wall of the adjacent standard (see Fig. 4).

The members 24, 25, are operated from the position shown in Figs. 1, 3 and 5 to the position shown in Fig. 6, the movement thereof being coordinated with the movement of each section A, so that the embossing elements 31 move therewith. In the arrangement herein shown, I provide one of the members (preferably the upper member 24) with a device in the path of movement of each section A, so that the advancing front end of the latter swings the members 24, 25, from their normal position forwardly, the spring 33 serving to move them back to normal position after the rear end of the section has passed the members. For this purpose, the arms 29 on the member 24 are provided on their front sides with brackets 34 to which are suitably bolted blocks 35, the brackets and blocks being formed with recesses in which are clamped the opposite ends of shafts 36. Each of the shafts 36 rotatably supports a roller 37, normally disposed in the path of movement of each section A. As shown in Figs. 3 and 6, the rollers 37 are so positioned that their peripheries are in contiguous relation to the forward edge of the embossing elements 26; accordingly, the advancing front end of the section engages with the rollers 37 immediately after it passes the elements 26 and as such end continues to advance, it swings the rollers outwardly and upwardly about the axis of the shaft 24a, the effect of which is to operate the members 24, 25, to the position shown in Fig. 6. As the section A continues to advance the rollers 37 ride thereon and thus maintain the members 24, 25, in operated position until the rear end of the section passes the rollers, whereupon the spring 33 will swing the members back to normal position. In the arrangement shown, the embossments are positioned adjacent to the front ends of the sections A, but by positioning the rollers in spaced relation to the forward sides of the members 24, 25, the embossments may be provided at a point remote from the front ends of the sections.

38, 39, indicate a pair of feed rolls keyed to shafts 38a, the opposite ends of the latter being mounted in bearing boxes which are suitably supported by the standards 9. The shafts 38a are geared together, and the lower shaft 38a is provided with a sprocket 39 which is engaged by a chain 40, driven by a sprocket 41 fixed to and driven by the lower shaft 7a, as shown in Fig. 3. The sprockets 39 and 41 are of similar size so as to drive the shafts 38a at the same speed as that of the shafts 7a.

Referring to Figs. 11 and 12 which show a modified form of construction for providing the embossments C, C', in each section, 8' indicates a pair of standards adapted to be mounted on the frame 1 between the standards 7 and 9 and supporting upper and lower cross members 42, 43, 43a, indicate a pair of plates disposed above and below the path of movement of the sections A and supported for swinging movement by parallel links 44 on the cross members 42, whereby the plates traverse arcs which substantially intersect the path of movement of the sections A. The links are pivoted at their inner ends on shafts 44a supported by lugs formed integrally with the plates 75

43, 43a and pivoted at their outer ends on shafts 44a supported by integral lugs 44x provided on the members 42. The opposed faces of the plates 43, 43a, are formed with recesses 45 in which are mounted dies 45' having on their opposed walls complementary embossing elements. The rear ends of the plates 43, 43a, are connected to springs 46, which are suitably anchored to brackets 46a and normally tend to swing the plates 43, 43a, 10 rearwardly, as shown in dotted lines, whereby they are separated and positioned to receive a section A between them, the rearward movement of the plates being limited by the engagement of the rear links 44 with stops 47. The upper plate 43 is 15 provided at its front end with rollers 48, mounted similarly to the rollers 37, so as to be engaged by the advancing end of each section A. The plates 43, 43a, are provided at their opposite ends with pairs of laterally extending pins 49 which slide in 20 vertically extending, parallel slots 49a formed in plates 50, the plates 50 serving to connect the plates 43, 43a, together whereby they swing in unison from one position to the other and back again. Accordingly, when each section engages 25 with and moves the rollers 48 to the dotted line position X shown in Fig. 11, both plates 43, 43a, will be operated and effect embossing of the section and through the engagement of the rollers 48 with the advancing section, they will remain 30 in operated position until the rear end of the section passes the rollers, whereupon the plates will swing rearward under the influence of the springs 46.

The machine herein disclosed is shown embossing a section of sheet material approximately ten feet long, but it will be understood that the sections may be of any desired length. The embossing rolls 2a', 3a', etc., are preferably driven at a rate of speed to feed the sections at approximately 180 feet per minute and they are delivered 40 successively to the shaping rolls 2a', each spaced from or timed with respect to the preceding section in relation to the time required for the return movement of the members 24, 25, after the rear end of each section has passed the actuating rollers 37 (Figs. 1 to 7) or rolls 48 (Figs. 11 and 12) for operative relation to the front advancing end of the succeeding section.

The sleeves 28 are positioned on the shafts 24a, 50 25a between a collar 51 and ring nuts 52 engaging threaded portions on the shafts, spacing 53 collars being provided to properly position the sleeves.

54 indicates supports for the sections extending between each set of rolls, between the rolls 7a' and the embossing members 24, 25, and also from a point which clears the rollers 37 to the rolls 38. The supports 54 are mounted on cross members rigidly carried by the standards. The 60 standards 2a, 3a, etc. on that side of the frame 1, remote from the shaft driving means, are adjustably mounted on the frame 1, whereby they may be positioned to accommodate roll carrying shafts of different lengths where found desirable for any reason.

The rollers 37 are positioned on the shafts 36 between washers, which are held in position by nuts 36' threaded on the shafts.

To those skilled in the art to which my invention relates many changes in construction and widely differing embodiments and applications of the invention will suggest themselves without departing from the spirit and scope of the invention.

75 My disclosures and the description herein are

purely illustrative and are not intended to be in any sense limiting.

What I claim is:

1. In a machine of the class described, the combination with a support, of guiding and supporting means thereon for sections of sheet material, including a set of driven rolls incorporated with said guiding and supporting means for feeding the sections therealong, a pair of members mounted above and below the path of movement 10 of the sections and swingable from one side of a median line to the opposite side thereof on axes at right angles to the direction of movement of the sections, said members being provided with complementary embossing elements arranged to 15 engage each section during movement thereof and emboss it, and means for swinging said members.

2. In a machine of the class described, the combination with a support, of guiding and supporting means thereon for sections of sheet material, including a set of driven rolls incorporated with said guiding and supporting means for feeding the sections therealong, a pair of members mounted above and below the path of movement 20 of the sections and swingable from one side of a median line to the opposite side thereof on axes at right angles to the direction of movement of the sections, said members being provided with complementary embossing elements arranged to 25 engage each section during movement thereof and emboss it, and means for swinging said members in the direction in which the sections 30 move, said members being provided with complementary elements arranged to engage each section during movement thereof and emboss it, and separate means for swinging said members in the opposite direction.

3. A machine as claimed in claim 2 wherein the swinging of said members in each direction is controlled by each section.

4. In a machine of the class described, the combination with a support, of guiding and supporting means for sections of sheet material, including a set of rolls for feeding the section therealong, a pair of members mounted above and below the path of movement of the sections and swingable from one side of a median line to the opposite side thereof on axes disposed at right angles to the direction of movement of the sections, said members being operatively connected for simultaneous movement in either direction, a device carried by one of said members in the path of movement of the sections and arranged when engaged by the advancing front end of each section to swing said members from the rear side of said median line to the forward side thereof, said members being provided with complementary elements arranged to emboss each section during the swinging movement of said members, and means for swinging said members in the opposite direction.

5. In a machine of the class described, the combination with a support, of guiding and supporting means for sections of sheet material, including a set of rolls for feeding the sections therealong, a pair of members mounted above and below the path of movement of the sections and swingable from one side of a median line to the opposite side thereof on axes disposed at right angles to the direction of movement of the sections, said members being operatively connected for simultaneous movement in either direction, a device carried by one of said members in the path of movement of the sections and arranged when engaged by the advancing front end of each section to swing said members from the rear side of said median line to the 60 forward side thereof.

forward side thereof, said members being provided with complementary elements arranged to emboss each section during the swinging movement of said members, said device being arranged to ride on each section after it has been embossed to hold said members in operated position, and a spring connected to one of said members and arranged to swing them in the opposite direction after the rear end of each section has fed past said device.

6. In a machine of the class described, the combination with a support, of guiding and supporting means thereon for sections of sheet material, including a set of driven rolls incorporated with said guiding and supporting means for feeding the sections therealong, a pair of members mounted above and below the path of movement of the sections and swingable from one side of a median line to the opposite side thereof on axes at right angles to the direction of movement of the sections, said members being provided with complementary embossing elements arranged to engage each section during movement thereof and emboss it, spring tension means normally tending to swing said members to the rear side of said median line in position to receive each section between them, and a device carried by one of said members and disposed in the path of movement of the sections when said members are in position to receive a section between them, whereby the advancing front end of each section operates through said device to swing said members to the opposite side of said median line.

7. In a machine of the class described, the combination with a support, of guiding and supporting means thereon for sections of sheet material, including a set of driven rolls incorporated with said guiding and supporting means for feeding the sections therealong, a pair of members mounted above and below the path of movement of the sections and swingable from one side of a median line to the opposite side thereof on axes at right angles to the direction of movement of the sections, said members being provided with complementary embossing elements arranged to engage each section during movement thereof and emboss it, spring tension means normally tending to swing said members to the rear side of said median line in position to receive each section between them, and a device carried by one of said members and disposed in the path of movement of the sections when said members are in position to receive a section between them, whereby the advancing front end of each section operates through said device to swing said members to the opposite side of said median line, said device being arranged to ride each section as it feeds forward, whereby said section holds said members in operated position until its rear end passes said device and permits said members to swing rearwardly under the influence of said spring tension means.

8. In a machine of the class described, the combination with a support, of guiding and supporting means thereon for sections of sheet material, a pair of members mounted above and below the path of movement of the sections and swingable from one side of a median line to the opposite side thereof on axes at right angles to the direction of movement of the sections, means for connecting said members together for simultaneous movement in either direction, said members being provided with complementary embossing elements arranged to engage each section

during movement thereof and emboss it, a device carried by one of said members and arranged to be engaged by each section to operate said members, means normally tending to swing said members to the rear side of said median line, and means for successively feeding sections of sheet material between said members.

9. In a machine of the class described, the combination with a support, of guide means thereon for sections of sheet material, a pair of spaced standards, upper and lower rock shafts mounted in said standards above and below the path of movement of the sections, a pair of members fixed to said shafts and swingable to either side of a plane cutting the axes of said shafts, the outer ends of said members being arranged to traverse arcs which substantially intersect the path of movement of the sections, complementary elements on the outer ends of said members arranged to emboss each section as said members swing from the rear side of said plane to the forward side thereof, means for connecting said members together for simultaneous movement in either direction, one of said members being provided with a device arranged in the path of movement of each section when said members are positioned at the rear side of said plane, whereby each section as it feeds forward swings said members to the forward side of said plane, means for returning said members to the rear side of said plane, and means for feeding sections of material along said guide means and between said members.

10. In a machine of the class described, the combination with a support, of guide means thereon for sections of sheet material, a pair of spaced standards, cross members arranged above and below the path of movement of the sections and supported by said standards, a pair of plates disposed above and below the path of movement of the sections and each swingably connected to the adjacent cross member by parallel links and arranged to traverse an arc which substantially intersects the path of movement of the sections, complementary elements carried by the opposed faces of said plates arranged to emboss each section as the plates traverse their arcs in the direction in which each section moves, means for connecting said plates together for simultaneous movement in either direction, a device carried by one of said plates and arranged to be engaged and moved by the advancing front end of each section, whereby the plates are operated in one direction, means for operating the plates in the opposite direction, and means for feeding sections of material along said guide means and between said plates.

11. In a machine of the class described, the combination with a support, of sets of rolls forming passes for sections of material and having complementary elements for embossing the sections longitudinally as the sections move between said rolls, a pair of members arranged to oscillate on axes parallel to said sets of rolls for embossing the sections transversely, means for connecting the members together for simultaneous movement in either direction, means for swinging said members in a direction opposite to that in which the sections feed, a device carried by one of said members and arranged to be engaged and operated by each section, whereby the section is embossed by said members as the section feeds therebetween, and means for driving certain of said sets of rolls to feed the sections between said sets of rolls and said embossing members.

12. In a machine of the class described, the combination with a support, of sets of rolls forming passes for sections of material and having complementary elements for embossing the sections longitudinally from end to end as the sections move between said rolls, a pair of members arranged to oscillate on axes parallel to said sets of rolls for embossing each said section transversely intermediate its front and rear ends, means for connecting said members together for simultaneous movement in either di-

rection, spring tension means normally tending to swing said members in a direction opposite to that in which the sections feed, a device carried by one of said members and arranged to be engaged and operated by each section, whereby the section is embossed by said members as the section feeds therebetween, and means for driving certain of said sets of rolls to feed the sections between said sets of rolls and said embossing members. 5

10
GEORGE E. KENTIS.
